UNITED STATES PATENT OFFICE.

WILLIAM M. HEUN, OF MCCOOK, NEBRASKA.

RAIL-JOINT.

No. 820,578.

Specification of Letters Patent.

Patented May 15, 1906.

Application filed October 28, 1905. Serial No. 284,502.

To all whom it may concern:

Be it known that I, WILLIAM M. HEUN, a citizen of the United States, residing at McCook, in the county of Red Willow and State 5 of Nebraska, have invented a new and useful Rail-Joint, of which the following is a specification.

This invention relates to rail-joints, and has for an object to provide a joint embodying new and improved features of simplicity, 10 utility, and efficiency.

A further object of the invention is to provide a rail-joint embodying improved means to prevent the depressing and hammering of 15 rail ends and click of passing wheels.

A further object of the invention is to provide a rail-joint embodying improved means to permit the contraction and expansion of the rails.

With these and other objects in view the present invention consists in the combination and arrangement of parts, as will be hereinafter fully described, shown in the accompanying drawings, and particularly pointed 25 out in the appended claims, it being understood that changes in the form, proportion, size, and minor details may be made without departing from the spirit or sacrificing any of the advantages of this invention.

In the drawings, Figure 1 is a perspective view of the improved rail-joint assembled. Fig. 2 is a perspective view of the rail ends disengaged. Fig. 3 is a transverse sectional view taken on line 3 of Fig. 1.

Like characters of reference indicate corresponding parts in all of the figures of the drawings.

In its preferred embodiment the improved rail-joint forming the subject-matter of this 40 application comprises the rail ends 10 and 11, respectively tapered, as at 12 and 13, to meet in a vertical plane, as 14, disposed obliquely to their lengths. Through the web of the rail are formed slots 15 and 16, at least one 45 of which, as 16, registers in the two rail ends when assembled. Within the tapered surface of the head of one rail end, as 10, is formed a groove 17, extending longitudinally of the taper, and rib 18 is formed along

the tapered surface of the opposed rail-head 50 and proportioned and disposed to be slidably engaged within the groove 17. The ends of this rib are beveled, as shown, so that the rails when forced together will be properly centered or alined. Fish-plates 19 19' of 55 substantially the usual form are provided, having openings for the receipt of bolts 20, registering with the slots 15 and 16.

With the parts assembled as in Fig. 1 the rib 18 is within the groove 17, whereby a longitudinal movement of the rail ends relative to each other is possible without a transverse movement of the tapered faces upon each other. During cold weather when the rails contract they will move longitudinally relative to each other at the joints, and owing to the taper the transverse thickness of the rails at the joint will be slightly reduced. As the bolts contract at the same time, the loosening of the joint will be to a great extent compensated for; but should any looseness occur no transverse movement of the rail ends is possible, owing to the rib and groove.

Having thus described the invention, what is claimed is—

1. A T-rail having oblique parallel ends, a groove within one end of the head of the rail and parallel with the rail-base, and a rib of uniform width and thickness upon the other end of the head of the rail and parallel with the rail-base, said rib and groove being of substantially the same proportions.

2. A rail-joint comprising T-rail ends having oblique meeting ends, one of said ends having a groove in the head thereof parallel with the rail-base and the other rail end having a similarly-disposed supporting and centering rib of uniform width and thickness adapted to be seated in the groove, said rib having beveled ends.

In testimony that I claim the foregoing as my own I have hereto affixed my signature in the presence of two witnesses.

WILLIAM M. HEUN.
